UNITED STATES PATENT OFFICE.

HENRY T. WINDT, OF TORONTO, ONTARIO, CANADA, ASSIGNOR TO THE
TORONTO WIRE MAT COMPANY, OF SAME PLACE.

DOOR-MAT.

SPECIFICATION forming part of Letters Patent No. 340,901, dated April 27, 1886.

Application filed April 3, 1884. Serial No. 126,489. (Model.) Patented in Canada April 30, 1884, No. 19,254.

To all whom it may concern:

Be it known that I, HENRY THEODORE WINDT, of the city of Toronto, in the county of York, in the Province of Ontario, Canada, have invented certain new and useful Improvements in Door-Mats; and I do hereby declare that the following is a full, clear, and exact description of the same.

The object of the invention is to devise a coiled-wire mat which will not curl up at its corners, and which will make an effective door-mat; and it consists, essentially, first, of a series of wire coils linked together parallel with each other and braced by a similar series of coils screwed into the mat at about right angles to the coils, the corners being stiffened by an angular bar inserted into the mat and extending diagonally from the corners; secondly, in providing a bracket for holding down the coiled-wire mat, as hereinafter more particularly explained.

Figure 1 is an enlarged plan of my improved mat, showing the manner of inserting the stiffening-bar. Fig. 2 is a perspective view of door-steps, showing my improved mat in position. Fig. 3 is a perspective view showing a portion of a stationary bracket for holding the mat down. Fig. 4 is a similar view of the hinged bracket. Fig. 5 is an edge view of the mat. Fig. 6 is an edge view of a portion of a mat, showing in section the hinged bracket and its locking-head.

The primary object of the invention is to provide a coiled-wire mat which will present a surface similar to a series of scrapers, the mat so formed having its corners stiffened, so as to prevent them curling. To form this mat I take a series of coils, A, and link them together parallel with each other. The mat thus formed of these coils A is braced by a similar series of coils, B, screwed into the mat at about right angles to the coils A at the point where the connecting-coils A intersect each other. The mat thus formed presents a surface composed of straight scrapers d. (Shown in Fig. 5.)

C is an angular stiffening-bar inserted into the mat, as shown in Fig. 1, extending diagonally from each corner of the mat. This stiffening-bar is woven into the mat, one leg being inserted on the top side, while the other leg ex-

tends below and passes on the bottom side of the mat, the coiled wires forming the mat running on about a line with the legs of the stationary bar C, so that the said bar can easily be inserted into position by partially withdrawing one of the coiled wires on the top side where the bar C on that side is to lie, and then withdrawing a similar coil on the bottom side at the point where the bar C is to rest on this latter side, when the said coils may be screwed back into position and the stiffening-bar secured. A mat formed by the coils running diagonally across its surface will present scraping-edges d, running parallel with the length of the mat, and will in that way form a good surface for scraping the feet on. A mat thus formed will not coil up at the corners, and the dirt scraped off will fall through the mat, and can easily be swept away when necessary. The mat can also be turned, so that it will last for a very long time. In Fig. 2 I show it applied to door-steps. The lower step shows a bracket, D, screwed into position. The next step exhibits the mat in the act of being dropped into its place. The third step shows the mat in place, and the top step shows the mat in its ordinary position for a door-mat, the mat shown on the steps being applied there for the purpose of preventing the steps wearing, and are suggested as a cheap and effective substitute for the iron and brass plates now employed for that service.

The bracket D, which, when used, is first secured in position, is provided with a lip, a, under which the outer edge of the mat formed by the last row of scrapers d is inserted. This bracket will alone be sufficient to secure the mat in position when it is held against the riser of a step or against any wall; but where the mat is located away from the riser or wall I may use two brackets D; or, in order to allow of the easy removal of the mat for sweeping beneath it, I may use a bracket, E, having a lip, b, similar to and for the same purpose of the lip a, said bracket E to be used in place of one of the brackets D. This bracket E is hinged at e, and is provided with a locking-head, F, which, when turned in one direction, fits into a slot made in the upper hinged half of the bracket E, thereby permitting it to be freely

opened; but when the bracket is to be locked down for the purpose of securing the mat in position, the head F is turned so as to lap over the edges of the slot, as shown in Fig. 4.

5 I should mention that the edges of the mat formed by the coils A and B are finished as indicated in Fig. 1, the ends f of one coil being bent around the spiral body of the coil next to it, thereby locking the coils together, and at 10 the same time forming a finished smooth edge somewhat stiffer than the body of the mat. I should also mention that although I think the angular stiffening-bar C to be the best plan for the purpose specified, straight bars inserted 15 near the edge of the mat might accomplish in a measure, if not altogether, the object secured by the stiffening-bar C.

No claim is made in this application to the wire fabric or the specific construction of the 20 retaining brackets herein shown and described, as I intend to make the same the subject-matter of separate applications.

What I claim as my invention is—

1. As an improved mat, a series of wire coils

linked together parallel with each other and 25 braced by a similar series of coils screwed into the mat at about right angles to the other coils, in combination with a stiffening-bar inserted into the corners of the mat, substantially as and for the purpose specified.

2. A mat composed of a series of coiled wires 30 meshed together, as specified, in combination with the hinged bracket E, provided with the lip b, and having a locking-head, F, substantially as and for the purpose specified.

3. A mat composed of a series of wire coils 35 linked together parallel with each other and braced by a similar series of coils screwed into the mat at about right angles to the other coils, and provided with a stiffener-bar inserted into the corners of the mat, combined with a bracket having a lip and a locking-head, substantially as and for the purpose specified.

Toronto, March 24, 1884.

H. T. WINDT.

In presence of—

CHAS. C. BALDWIN,

F. BARNARD FETHERSTONHAUGH.
